Primary Examiner—Wallace R. Burke*Assistant Examiner*—Marcus Jackson*Attorney, Agent, or Firm*—Frishauf, Holtz, Goodman & Woodward**[57] CLAIM**

The ornamental design for a compact fluorescent lamp, as shown and described.

DESCRIPTION

FIG. 1 is a perspective view of a compact fluorescent lamp showing my new design;

FIG. 2 is a side elevational view thereof, with the opposite side being a mirror image;

FIG. 3 is a bottom plan view thereof;

FIG. 4 is a top plan view thereof;

FIG. 5 is a perspective view of a second embodiment thereof;

FIG. 6 is a side elevational view thereof, with the opposite side being a mirror image;

FIG. 7 is a bottom plan view thereof;

FIG. 8 is a top plan view thereof;

FIG. 9 is a partial sectional view taken along line IX-IX of FIG. 2; and,

FIG. 10 is a partial sectional view taken along line IX-IX of FIG. 6.
